(57) **CLAIM**

The ornamental design for a corner shelf rack system, as shown and described.

DESCRIPTION

FIG. 1 is a top, front perspective view of a corner shelf rack system showing a first embodiment of the new design; FIG. 2 is a right elevation view of the invention illustrated in FIG. 1;

FIG. 3 is a left rear elevation view of the invention illustrated in FIG. 1;

FIG. 4 is a left elevation view of the invention illustrated in FIG. 1;

FIG. 5 is a right rear elevation view of the invention illustrated in FIG. 1;

FIG. 6 is a top view of the invention illustrated in FIG. 1; FIG. 7 is a bottom view of the invention illustrated in FIG. 1;

FIG. 8 is a top, right, rear perspective view of the invention illustrated in FIG. 1;

FIG. 9 is a top, front perspective view of a corner shelf rack system showing a second embodiment of the new design; FIG. 10 is a right elevation view of the invention illustrated in FIG. 9;

FIG. 11 is a left rear elevation view of the invention illustrated in FIG. 9;

FIG. 12 is a left elevation view of the invention illustrated in FIG. 9;

FIG. 13 is a right rear elevation view of the invention illustrated in FIG. 9;

FIG. 14 is a top view of the invention illustrated in FIG. 9; FIG. 15 is a bottom view of the invention illustrated in FIG. 9; and,

FIG. 16 is a top, right, rear perspective view of the invention illustrated in FIG. 9.

The broken lines in the drawings depict portions, of the corner shelf rack system that form no part of the claimed design. The corner shelf rack system is shown with symbolic break lines in its height. The appearance of any portion of the article between the break lines forms no part of the claimed design.

1 Claim, 16 Drawing Sheets
